US0D1011941S

(12) **United States Design Patent** (10) **Patent No.:** **US D1,011,941 S**
(45) **Date of Patent:** **** Jan. 23, 2024**

(54) **MASS SPECTROMETER**

(71) Applicant: **Micromass UK Limited**, Wilmslow (GB)

(72) Inventors: **Arthur Blake**, Manchester (GB); **Andrew Pawson**, Manchester (GB); **Peter Carney**, Dukinfield (GB)

(73) Assignee: **Micromass UK Limited**, Wilmslow (GB)

(**) Term: **15 Years**

(21) Appl. No.: **29/857,936**

(22) Filed: **Oct. 26, 2022**

(30) **Foreign Application Priority Data**

Apr. 29, 2022 (GB) 6205108

(51) **LOC (14) Cl.** **10-04**

(52) **U.S. Cl.**

USPC **D10/81**; D24/216

(57) **CLAIM**

The ornamental design for a mass spectrometer, as shown and described.

DESCRIPTION

FIG. 1 is a front perspective view of a mass spectrometer showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown are included for the purpose of illustrating portions of the mass spectrometer that form no part of the claim.

1 Claim, 7 Drawing Sheets
